WINDING STRANDULAR MATERIAL

Willem J. D. van Dobbenburgh, Enka, N. C., assignor to American Enka Corporation, Enka, N. C., a corporation of Delaware

Application May 28, 1940, Serial No. 337,701

3 Claims. (Cl. 57—62)

This invention relates to the twisting of threads and more particularly to methods of and apparatus for eliminating irregularities normally occurring in threads of synthetic character in their passage between a supply package and a draw-off device in an up-stroke twisting machine.

In the twisting of thread on an upward twister, the thread, after being withdrawn overhead from a rapidly rotating supply bobbin, is passed through an adjacent pigtail guide and collected upon a take-up spool. The thread in this manner receives a definite number of turns per inch, in part depending upon the rate at which it is withdrawn. The rapid rotation of the supply bobbin causes the thread to balloon outwardly therefrom between the point of delivery of the thread from the bobbin and the pigtail guide, said guide serving to confine the thread at that point.

While a twisting machine of the type discussed above is quite satisfactory as regards most of the aspects of its operation, it has been noted that rayon filaments twisted thereon to form a thread are frequently impaired during the twisting operation, such impairment involving the production of irregularities in the thread known to the art as loops and corkscrews. Of course, the presence of such imperfections in the thread seriously impairs the uniformity thereof and, as a result, the product is rendered unsatisfactory for many industrial and textile purposes.

While the exact reason for the production of irregularities in thread twisted according to conventional methods involving the use of known machinery is not fully understood, it is believed that the centrifugal force set up by the rapid rotation of the supply bobbin causes an initial displacement of individual filaments in the thread layers in the package. This initial displacement is more pronounced in the outer layers of the package because after the necessary processing steps, the outer layers are loose and softer than the inner layers. When the filaments are drawn off at a high rate of speed they become even more disturbed and loosened as they have no opportunity to become realigned and thus are entangled with other layers of thread. In some instances, sticky substances remaining in the thread from previous treating steps may cause filaments to adhere to the thread package, the result being that certain filaments are stretched and become looped about the thread mass thereby producing undesirable irregularities. The loop and corkscrew formation is not as evident

in the inner layers of filaments probably due to the fact that they are more compact and firm, and also because as the diameter of the package decreases, the centrifugal force decreases.

While such irregularities are likely to be produced in the twisting of any threads they are particularly noticeable in the twisting of rayon threads, inasmuch as rayon threads are made up of large numbers of individual filaments of a delicate character, which, prior to twisting, are in substantially parallel relation to each other. Heretofore, such defects as loops and corkscrews have been regarded as normal imperfections in rayon threads.

15 A number of efforts have been made to overcome these difficulties encountered in the twisting of rayon threads. For example, friction members have been interposed in the path of the thread intermediate the supply bobbin and the take-up device, with a view to at least in part eliminating the occurrence of loops and corkscrews by imparting a drag on the thread. Such devices may cause localized overstretching, however, and thereby merely effect the substitution of one type of non-uniformity for another. It has been found that by slowing down the entire twisting operation the formation of loops and corkscrews can be avoided. However, such a method is not entirely satisfactory because its employment so retards the rate of production of thread as to cause a serious increase in the cost of operation of the manufacturing plant.

20 It is therefore an object of this invention to provide a process wherein the thread constituting a complete package of rayon may be twisted at a high average speed without the formation of irregularities therein while the application of mechanical braking means to the thread is entirely avoided.

25 It has been discovered that a high average winding speed may be maintained without the formation of loops and corkscrews by effecting the twisting of different portions of the yarn constituting the package at different speeds, lower speeds being employed as regards portions of the thread on the package which have been found to be more susceptible to injury than other portions.

30 It is further contemplated by this invention to provide a method and apparatus for twisting yarn at varying linear speeds whereby to maintain maximum efficiency of operation in conjunction with the production of a superior product.

35 Other objects and advantages of this invention will be apparent from a consideration of the fol-

lowing detailed description of a preferred embodiment thereof in conjunction with the accompanying drawing wherein:

Figure 1 is a diagrammatic view in side elevation of a thread twisting unit; and

Figure 2 is a view in front elevation of the unit shown in Figure 1.

It will be understood that the twisting assembly shown in Figures 1 and 2 may constitute but a single unit of a machine comprised of a large number of such units intended for simultaneous operation and adapted for the concurrent twisting of thread from a large number of supply packages. Referring in greater detail to the drawings, the unit disclosed consists of a thread package 10, a pigtail guide 11, a traverse mechanism 12, and a draw-off spool 13. The thread is twisted in its passage between package 10 and draw-off spool 13 as a result of the rapid rotation of the former. This rotation is effected by mounting package 10 on a spindle 14 which is connected to a whorl 15, the cylindrical surface of which contacts a belt 16 driven from a source not shown.

The package 10 consists of a large number of convolutions of rayon thread 17 and, as the package is rapidly rotated, this thread is drawn from the outside of the package upward along the axis of rotation thereof through pigtail guide 11 to traverse mechanism 12 and onto draw-off spool 13. The draw-off spool is mounted on shaft 18 and is driven by a generally cylindrical roller 19, the cylindrical surface of which initially contacts the surface of the spool and later, as the twisting operation progresses and thread is wound thereon, the roller contacts the wound thread body. Roller 19 is driven through shaft 20 to which it is keyed. Shaft 20 is actuated from a source of power not shown and, according to conventional practice, the drive for shaft 20 is connected with the drive for belt 16 to maintain a constant speed ratio between the two. It will be understood that adjustment in the ratio between these two drives may be effected for the purpose of varying the degree of twist imparted to the thread.

Since roller 19 contacts the surface of the thread body wound on draw-off spool 13, shafts 18 and 20 will tend to move apart as succeeding convolutions of wound thread increase the effective radial thickness of spool 13. For this reason shaft 18 is so journaled as to permit vertical movement toward and away from roller 19 while the thread surface on spool 13 maintains continuous contact therewith. As the thread builds up on draw-off spool 13 the speed of rotation of shaft 18 will be somewhat reduced, but because of the surface contact between roller 19 and spool 13 the thread take-up will continuously equal the peripheral speed of roller 19.

The thread, after its passage through pigtail guide 11, is laid up on draw-off spool 13 by a traverse mechanism of conventional form designated by the numeral 12. Traverse mechanism 12 is driven from the same source as roller 19 and, as a consequence, will distribute thread onto spool 13 in proportion to the speed at which said spool is driven. It will be recognized that all of the above described twisting assembly is quite conventional and well known in the art.

As above indicated, package 10 includes a wound body of rayon thread. Packages of this character are ordinarily made up from freshly spun artificial filaments which are wound into package form and are thereafter subjected to treatments such as desulphurizing, washing,

bleaching, drying and so forth. It is after these treatments have been completed that the twisting of the thread is accomplished. It has been discovered that the thread constituting a package 5 so prepared and so treated does not react uniformly to twisting. It has been determined that the outer convolutions of thread of a package, normally about 8000 yards or about one-third of the package, cannot be twisted at ordinary speeds 10 without the production of undesirable loops and corkscrews in the twisted thread. On the other hand, the inner convolutions of yarn constituting approximately two-thirds of a package of rayon thread can be twisted at such speeds, for example, 15 at a linear speed of 33 yards per minute. This figure is calculated for 6000 spindle revolutions per minute for a twist of 5 turns per inch. With a spindle speed of 6000 revolutions per minute given, the take-up speed will, of course, be different when 6 turns are inserted instead of 5 turns. 20 A figure in practical use is 6100 revolutions for 5 or 6 turns. Driving roller 19, having a diameter of $3\frac{3}{4}$ inches, is caused to rotate at about 99 R. P. M. to produce this linear speed. It has been 25 further discovered that the initial convolutions of yarn, the outer one-third of the package, can be twisted at a spindle speed of 4000 R. P. M. without injury to the thread incident to the occurrence of loops and corkscrews therein. To capitalize 30 on those discoveries, the twisting operation is carried out at two speeds, an initial subnormal speed to avoid the production of loops and corkscrews while the outer convolutions of thread are twisted, followed by the resumption of a normal 35 speed in twisting the remainder of the thread constituting the package.

While the theory involved in avoiding the formation of irregularities in twisted thread by operating the twister at the speeds indicated above 40 is not fully understood, it is known that this method of operation is quite successful and that the speeds may be modified to a certain extent without injury to the thread. It seems that because of the thickness of the package at the beginning 45 of the twisting operation there is a tendency toward entanglement, while during the later stages of twisting, when the package is partially depleted, this tendency does not exist.

To effect the alteration of the twisting speed 50 without interfering with the degree of twist imparted to the thread, a two-speed electric motor is used to drive belt 16, shaft 20 and its rollers 19, as well as traverse mechanism 12. Alternatively, 55 a motor may be employed wherein the speeds are varied over wide ranges by means of a frequency changer. Since these driven elements are conventionally operated in synchronism their operation at two different speeds will not alter the degree of twist imparted to the yarn but will permit the twisting of the thread constituting the outer one-third of the package at a slower rate to avoid the production of loops and corkscrews while the remainder of the package may be twisted at a usual speed to promote manufacturing efficiency.

60 A manually operated switch may be employed to selectively control the speeds of the motor, or the switch may be associated with shaft 18 so that upon completion of the radial movement of said shaft in response to the winding of approximately one-third of a package on draw-off spool 13, the motor will be caused to operate at increased speed.

In the twisting of some rayon yarns for certain uses, the collecting spools may be very large 70 and will receive the total thread from a plurality

of supply packages. Of course, when rayon thread is so collected, after twisting, it is apparent that the draw-off speed and speed of rotation of the bobbin must be reduced during the winding-off of the initial convolutions of each of the packages employed in making up the wound spool. When the thread on more than one package is wound on a single draw-off spool, the switch associated with shaft 18 can be employed only in modified form.

A manually operated change-speed transmission has been employed with success to vary the effective speed of the motor as regards the various units of the twisting assembly instead of the two-speed motor described above.

Having now described the invention in its preferred form, it is understood that variations and modifications may be made therein without departing from the spirit of the invention, and it is desired that the scope thereof be limited only by the appended claims.

What is claimed is:

1. A method of twisting succeeding portions of a single rayon thread consisting of a plurality of substantially parallel continuous filaments which have been cross wound in package form in radially superposed layers, in the path of travel of the thread from said package to a collecting device whereon it is again wound in package form at such high average spindle speeds that the thread balloons radially from the delivery package due to the centrifugal force generated thereby, comprising, rotating the thread package, drawing off from the outside of said package succeeding portions of thread by removal of successive cylindrical layers thereof, said thread being thrown off in a substantially radial direction from said package in the form of a balloon due to the centrifugal force of said package, drawn along the axis of rotation thereof and twisted by the rotation thereof, collecting the thread drawn off, initially temporarily reducing the draw-off speed and in proportion thereto the speed of rotation of the thread package while approximately one-third of the outer radially superposed convolutions of thread are twisted and thereafter resuming a high draw-off speed and proportionate speed of rotation of the thread package while the remainder of the component thread of the package is twisted and maintaining said high draw-off speed throughout the remainder of unwinding and as all portions of the

thread adjacent the package axis are thrown off, whereby the occurrence of irregularities in the thread is avoided.

2. A method of twisting succeeding portions of a single substantially parallel filament rayon thread cross wound into package form which comprises, rotating such a package of such thread at high speed to throw off succeeding portions of thread radially from the outside of said package to effect progressive reduction in radius of the package by successive removal of cylindrical layers of thread therefrom, drawing said thread as thrown off along the axis of rotation of the package, initially temporarily reducing the drawoff speed and proportionately the speed of rotation of the thread package while the outer convolutions of thread are drawn and twisted, and thereafter resuming a high drawoff speed and proportionate speed of rotation of the thread package while the remainder of the package is twisted, the speed of rotation of the package being uniformly high as all portions of thread adjacent the package axis are thrown off.

3. A method of twisting succeeding portions of a single substantially parallel filament rayon thread cross wound into package form which comprises, rotating such a package of such thread at high speed to throw off succeeding portions of thread radially from the outside of said package to effect progressive reduction in radius of the package by successive removal of cylindrical layers of thread therefrom, drawing said thread as thrown off along the axis of rotation of the package, initially temporarily reducing the drawoff speed and proportionately the speed of rotation during the winding of the remainder of the convolutions of thread are drawn and twisted, and thereafter resuming a high drawoff speed and proportionate speed of rotation of the thread package while the remainder of the package is twisted, the speed of rotation of the package being uniformly high as all portions of thread adjacent the package axis are thrown off, said initial speed of rotation of the thread package being at least 4000 revolutions per minute, which speed is maintained for at least the winding of one-third of the package and being in a ratio of about 2 to 3 with respect to the speed of rotation of the thread package while the outer package.

WILLEM J. D. VAN DOBBENBURGH.
